UNITED STATES PATENT OFFICE.

EMERICK WESTER, OF EASTON, PENNSYLVANIA.

MILK-BOTTLE CAP.

1,352,334.

Specification of Letters Patent.

Patented Sept. 7, 1920.

Application filed April 30, 1920. Serial No. 377,868.

To all whom it may concern:

Be it known that I, EMERICK WESTER, a citizen of the United States, residing at Easton, in the county of Northampton and State of Pennsylvania, have invented new and useful Improvements in Milk-Bottle Caps, of which the following is a specification.

This invention relates to milk bottles, particularly to closure caps therefor, and has for its object the provision of a metallic concavo-convex cap adapted for association with and disposition within the annular groove at the mouth of a milk bottle and having a peripheral flange bearing against the wall of the groove, the cap being normally disposed with its convex side uppermost and being flexible whereby it may be depressed to reverse the convexity for withdrawing the flange from engagement with the groove.

An important object is the provision of a cap of this character which will be simple and inexpensive in manufacture, which will be economical in use as it may be used indefinitely, which will be sanitary, and a general improvement in the art.

With the above and other objects and advantages in view, the invention consists in the details of construction to be hereinafter more fully described and claimed, and illustrated in the accompanying drawings in which—

Figure 1 is a longitudinal sectional view through the mouth and neck of a milk bottle, showing my cap applied thereto and in normal position, and

Fig. 2 is a similar view showing the cap depressed to disengage its flange from the bottle.

Referring more particularly to the drawings, the letter A designates the neck of a milk bottle provided with the usual groove B. In carrying out my invention I provide a cap 10 formed as a metallic disk concavo-convex in cross section and formed with an

annular flange 11. The cap 10 is adapted for disposition upon the bottle in abutting engagement with the shoulder formed by the groove and with the flange 11 flaring outwardly and frictionally engaging the wall of the groove. The cap is applied by merely pressing it into position.

When it is desired to remove the cap, it is merely necessary to press downwardly upon the center thereof whereby to reverse its convexity, as shown in Fig. 2, whereupon the flange 11 will be retracted from engagement with the wall of the groove B in an obvious manner. When the cap is to be reapplied it is merely necessary to press it and return it to its original position shown in Fig. 1. When the cap has been depressed to withdraw the flange 11 from the wall of the groove it will be observed that the operator may readily grasp the flange so as to lift the cap from its seat.

From the foregoing description and a study of the drawing it will be apparent that I have thus provided an extremely simple and yet highly efficient closure cap for milk bottles which will not only be easy to use and sanitary but which will also be durable and economical.

Having thus described my invention, I claim:

A closure cap adapted for disposition within the mouth of a milk bottle, the mouth having an annular groove, comprising a disk of flexible metal concavo-convex in cross section and formed with an annular flange extending upwardly, the cap being normally disposed with its convex side uppermost with said flange inclining outwardly and frictionally engaging the wall of the groove, and the cap being capable of being pressed downwardly whereby to reverse convexity thereof to cause the flange to be inclined inwardly whereby to withdraw it from engagement with the wall of the groove.

In testimony whereof I affix my signature.

EMERICK WESTER.
